Inventor:
Edwin C. Washburn
By his attorney
James F. Williamson

UNITED STATES PATENT OFFICE.

EDWIN C. WASHBURN, OF ENGLEWOOD, NEW JERSEY.

LEVER DRAFT GEAR.

Application filed July 2, 1921. Serial No. 482,037.

This invention relates to a draft gear of the type used in railway cars, and is designed to yieldingly take up the shock caused by starting or stopping the car.

5 It is an object of this invention to construct a draft gear comprising yielding elements, the resilient action of which is controlled by lever devices so arranged that the leverage changes as the resilient movement 10 is effected.

It is another object of the invention to construct such a draft gear of simple and efficient form, in which the resilient devices are enclosed in a casing, which, likewise, 15 form the fulcruming means for the said lever devices.

These and other objects of the invention will be fully set forth in the following description made in connection with the accompanying drawings in which like reference characters refer to the same parts throughout the different views, and in which 20

Fig. 1 is a plan view of the device, the end thereof being shown in section;

25 Fig. 2 is a view in side elevation of the device, some of which is shown in section;

Fig. 3 is a transverse vertical section taken on the line 3—3 of Fig. 1; and

30 Fig. 4 is a transverse vertical section taken on the line 4—4 of Fig. 1.

Referring to the drawings, in Fig. 1 are shown the draft members or sills 1 of the railway car which comprise oppositely disposed channel members. The members 1 35 are provided with stop members 2 and 3 of suitable form and secured thereto, respectively, at the rear and front portions thereof, and the stop devices 3 are provided with elongated slots 3^a which also extend through 40 the webs of the channel members 1. A coupler head or yoke head 4 has its inner portion disposed between the members 3 and an elongated slot 4^a also extends laterally through this head. A key member 5 substantially fitting the slot 4^a extends 45 therethrough and through the slots 3^a, being held in place by suitable pins or keys 5^a. The coupler butt 4 is provided at its top and bottom with pockets or recesses into which 50 extend the ends of a draft yoke 6, which ends are secured in said pockets by a filler of cast metal extending therearound and through holes in said ends and in the sides of said pockets. The draft yoke 6 is of 55 general U shape and a buffer plate 8 is held

at its rear end by flanges projecting at each side thereof. A rear follower plate 9 having plane front and rear surfaces, is disposed between the sills 1 and the sides of the yoke 6 and is arranged to abut against the forward end of the stops 2. A similar follower plate 10 also extends between the sills 1 and the arms of yoke 6 and also has plane surfaces arranged to contact with the stops 3, the rear end of the coupler head abutting 60 the plate 10 at the front side thereof.

A casing 11 of square or rectangular shape has a flaring portion adjacent its front end, the extreme front end being again formed of square or rectangular shape and said 65 casing is designed to contain nested coiled springs 12 and 13 which abut at their rear ends against the surface of the follower plate 9. A spring buffer or follower plate 14 has a plane surface abutting the front 70 ends of the springs 12 and 13 and has a central projection extending into the spring 13. The front surface of the plate 14 is provided with a central curved depression 75 surrounded by a raised portion convex in cross section, as clearly shown in Fig. 1. The casing 11 is provided at each side in its inclined flaring portion with slots or apertures 11^a and levers 15 having a height substantially equal to the height of the front 80 portion of the casing 11, having pyramidal lugs 15^a projecting into the apertures 11^a. The levers 15 are formed at their outer side portions with plane surfaces and on their inner faces, are formed with concave surfaces merging at their extreme inner edges into a slight convex surface. As seen in 85 Fig. 1, the convex surfaces of the inner sides of the levers 15 conform generally to concave surfaces in the front end of the plate 95 14. The outer or front sides of the levers 15 contact with the rear surface of the follower plate 10 and these front surfaces of the levers 15 are formed of convex curvature of rather large radius. The outer and 100 inner surfaces of the levers 15 are joined at their inner ends by slightly convex surfaces. It will be noted that the outer ends of the levers are somewhat closely confined 105 between the periphery of the plate 14 and the front rectangular portion of the casing 11 said lever thus being held in position, the rear ends of said levers forming shoulders abutting the flaring sides of the casing 11 adjacent the apertures 11^a. 110

The operation of the draft gear is as follows:

Assuming the pulling stress being applied to the coupling head 4, the same will be transmitted through the yoke 6 to the follower plate 9, which will, in turn, transmit the stress through the springs 12 and 13 to the plate 14 and thence through the levers 15 to the follower plate 10, which will abut against the stops 3 and thus transmit the said pulling strain to the sills 1 of the car. The springs 12 and 13 will be compressed and the rear end of the casing 11 will soon contact with the follower 9. It will be noted that with the parts in the position shown in Fig. 1, which may be called a normal position, the stress is applied to the springs through the plate 14 and levers 15 by the follower plate 10 at substantially the inner edge *a* of the levers 15, and at the same time, the stress is applied to the plate 14 by the levers at substantially the point marked *b*. The power arm of the levers is thus much longer than the weight arm and considerable leverage is exerted on the plate 14 and the springs. As the springs compress by the rearward motion of the plate 14, the levers will swing rearwardly fulcruming about their rear surfaces which are in contact with the casing 11 and the point of contact thereof, with the follower plate 10 will move outwardly toward the fulcrum of said levers. At the same time, the point of contact of the inner surfaces of the levers with the spring follower plate 14 will move inwardly. The leverage exerted upon the springs will, therefore, change from its most advantageous position, as shown in Fig. 1, to its least advantageous position when the springs are entirely compressed or the limit of movement of the draft gear is taken up. This movement will be determined by the key 5 engaging the ends of the slots 3^a. The yielding resistance therefore to the shocks is least at the beginning of the movement and gradually increases to the limit of the movement. The shocks will thus be gradually and easily absorbed and the stress on the coupling devices and sills gradually relieved. The levers 15 have considerable freedom of movement but at all times will be held in the casing 11 and between the follower plates 10 and 14. When the stress is relieved, the springs will expand and the parts will again be moved to the position shown in Fig. 1. When the shock is transmitted to the device in the opposite direction, as when a push is exerted on the coupler head 4, the parts will function in the same manner except that the follower plate 9 will then contact with the stops 2 and the follower plate 10 will move away from stops 3 to swing the levers 15 and compress the springs.

From the above description it is seen that applicant has produced a simple and yet a very efficient form of draft gear, and one comprising few parts, all of which can be made strong and rugged. The parts require little finishing and can be very easily assembled.

It will, of course, be understood that various changes may be made in the form, details and proportions of the device without departing from the scope of applicant's invention, which, generally stated, consists in the matter shown and described and set forth in the appended claims.

What is claimed is:

1. A draft gear for railway cars having in combination a casing, resilient means therein, levers having one convex and one concave side loosely pivoted at one end to said casing and abutting the same, a follower plate disposed between said means and levers abutting said means and having convex surfaces respectively engaging and of slightly smaller radius than the concave sides of said levers, and a follower plate and a flat plane surface engaging the convex side of said levers.

2. The structure set forth in claim 1, apertures in said casing, and lugs projecting from said levers into said apertures and forming shoulders which contact said casing, thus forming a pivotal connection of the levers to said casing.

3. A draft gear for railway cars having in combination, spring devices, an open ended casing enclosing said devices, said casing having an outwardly inclined portion adjacent one end and having apertures formed in said inclined portion at opposite points thereof, curved lever members having lugs projecting from one end and disposed in said apertures, a member in said casing in contact with said springs at its inner side and in contact with said levers at its outer side and a member also contacting said levers at their outer sides, said members being arranged for movement to compress the spring devices, and the surfaces of said members and said levers being so formed that the leverage exerted to compress the springs decreases as the springs are compressed.

4. A draft gear for railway cars having in combination, springs, an open ended casing surrounding said springs and being formed adjacent one end with an outwardly flaring portion and having its extreme end formed with its opposite sides parallel, said casing having apertures formed in said flaring portion at opposite points thereof and curved levers having lugs projecting from their end surfaces and forming shoulders therewith, said lugs being disposed in the apertures in said casing, and means for swinging said levers to compress the springs,

said levers and means being so arranged that the leverage tending to compress the springs decreases as the levers are swung.

5. A draft gear for railway cars having in combination, a resilient compressible device, rigid means disposed at the side thereof of having an aperture therein, a follower plate engaging said device and movable to compress the same, a lever having a shoulder thereon and a tongue projecting from said shoulder and passing through said aperture, said lever engaging said follower plate, and a member movable relatively to said rigid means engaging the other side of said lever, said lever being curved and movable about said shoulder whereby its leverage decreases as said resilient device is compressed.

6. A draft gear for railway cars comprising, a resilient device, a follower plate engaging the same and having an annular convex surface, a pair of oppositely disposed levers having a concave side engaging said surface and having their opposite sides convex, and a flat member engaging said latter sides to swing said levers and compress said resilient means whereby the leverage decreases as said resilient means is compressed.

7. A draft gear comprising, a resilient device, a member at the side of said device having a portion inclining outwardly therefrom and an adjacent portion extending parallel with the longitudinal axis of said device, said member having an aperture through said inclined portion, a lever having a shoulder abutting said inclined portion and a tongue projecting through said aperture, a

follower plate engaging said resilient device and movable to compress the same engaged by one side of said lever, and a member movable relatively to said first mentioned member engaging the other side of said lever to swing the same to compress the resilient device.

8. A draft gear for railway cars having in combination, a casing, a resilient means therein, a follower plate engaging said means with one side and having its other side curved, levers loosely pivoted in said casing and having inner surfaces curved substantially in conformity to the curved surface of said plate and having a point of contact therewith and a flat follower plate engaging the outer sides of said levers to swing the same and compress said resilient means, said surfaces, said plate and lever being so formed that the point of contact moves away from the fulcrums of said levers as said resilient means are compressed.

9. A draft device having in combination, a follower plate having a plane surface, a pair of levers extending inwardly across said plate having convex surfaces contacting the surface thereof, a casing to which said levers are pivoted at their outer ends said levers having concave surfaces on their sides opposite said convex surfaces, a follower plate having convex surfaces substantially fitting said concave surfaces and a resilient means in said casing engaging said follower plate at the side opposite said levers.

In testimony whereof I affix my signature.
EDWIN C. WASHBURN.
